HIGH VOLTAGE TRANSFORMER

William R. Welty, Fullerton, and Leo W. Wilson, Huntington Beach, Calif., assignors to Hughes Aircraft Company, Culver City, Calif., a corporation of Delaware

Filed Nov. 19, 1965, Ser. No. 508,734

7 Claims. (Cl. 323—48)

This invention relates to pulse-type transformers and more particularly to an apparatus including mutually coupled windings connected in a manner to achieve an extremely high voltage handling capability.

The conventional transformer is wound on a single core in a manner such that the full secondary voltage appears between windings as well as between core and secondary. In transformers with appreciable bandwidth and reasonable efficiency, this type of fabrication is generally limited to a maximum safe voltage of a small fraction of a megavolt.

It is therefore an object of the present invention to provide an improved transformer configuration capable of producing a very high secondary voltage without breakdown.

Another object of the invention is to provide a transformer that is capable of producing very little phase or amplitude distortion over a very wide frequency range.

Still another object of the invention is to provide a transformer that may be designed to produce much larger secondary surge impedances than possible with conventional methods.

A further object of the invention is to provide a transformer that is of significant advantage in situations requiring the transformation of broad spectral electrical wave functions to very high voltage amplitudes with a minimum of distortion.

A still further object of the invention is to provide a transformer apparatus that has typical applications in a high voltage pulse modulator for klystrons, traveling wave tubes, X-ray tubes or gamma ray tubes.

In accordance with the present invention, a series of individual transformers are interconnected in such a manner that the secondary voltage is divided equally between them. The individual cores of the respective transformers are both insulated from ground and connected to points of the apparatus having the most appropriate potential relative to the respective windings. The secondary to primary induced voltage ratio of each transformer is slightly greater than unity. The slight excess is to compensate for copper and coupling loss in the transformer windings and associated delay lines to leave an effective ratio of unity. In the apparatus of the invention, all the primary windings are connected in series and all the secondaries are connected in series in the same order. In addition, delay lines are connected from the primary to the secondary windings in a manner to provide equal delay to the primary excitation waveform to enhance the high frequency response of the transformers.

The above-mentioned and other features and objects of this invention and the manner of obtaining them will become more apparent by reference to the following description taken in conjunction with the accompanying drawing, wherein the figure illustrates a schematic circuit diagram of a preferred embodiment of the invention.

Referring now to the drawing, there is shown a schematic circuit diagram of the transformer apparatus of the present invention for providing an output voltage nE where n is a positive integer no less than two and E is the input voltage, i.e., n is ratio of secondary voltage to primary voltage. In particular, the apparatus of the invention includes transformers T_1 , T_2 , T_3 , T_{n-3} , T_{n-2} and T_{n-1} . Transformers T_1 through T_{n-1} have primary windings 10, 11, 12, 13, 14, 15; secondary windings 20, 21, 22, 23, 24

2

and 25; and cores 30, 31, 32, 33, 34 and 35 respectively. A "reference surge impedance" Z , for the transformer apparatus is defined as the

$$\sqrt{(\text{input impedance})(\text{output impedance})}$$

whereby the surge impedance is Z/n at the input and nZ at the output. The turns ratio of each of the transformers T_1 through T_{n-1} is made to approach unity after taking core and copper losses into consideration and the winding surge impedance of the respective transformers is defined as

$$\frac{120\pi Nt}{\sqrt{\epsilon}}$$

15 where $\pi=3.1416$, N =turns per unit length, t =thickness of insulation pad between primary and secondary windings of the respective transformers T_1 through T_{n-1} and ϵ =dielectric constant of the insulation pads. On this basis, the transformer T_1 is designed to have a winding surge impedance equal to

$$\frac{Z}{n-1}$$

the transformer T_2 a winding surge impedance equal to

$$\frac{Z}{n-2}$$

the transformer T_3 a winding surge impedance equal to

$$\frac{Z}{n-3}$$

the transformer T_{n-3} a winding surge impedance equal to $Z/3$; the transformer T_{n-2} a winding surge impedance equal to $Z/2$; and the transformer T_{n-1} a winding surge impedance equal to Z .

35 The primary windings 10 to 15 and the secondary windings 20 to 25 of transformers T_1 through T_{n-1} are serially connected in the order named as shown in the drawings. In addition, the respective primary and secondary windings 10-15 and 20-25 of transformers T_1 through T_{n-1} are all poled in the same direction and the cores 30, 35 are referred to an extremity of the primary windings 10-15 respectively. Also, the remaining extremity of primary winding 10 of transformer T_1 is connected to a terminal 39 which is referenced to ground and the remaining unconnected extremity of secondary winding 20 thereof is connected to an input terminal 40. As previously specified, the input impedance at the terminals 39, 40 is equal to Z/n . The remaining unconnected extremity of secondary winding 25 of transformer T_{n-1} is connected to an output terminal 42. The surge impedance relative to ground at the output terminal 42 looking into the apparatus of the invention is equal to nZ .

In addition to the above, the apparatus of the invention includes delay lines D_1 , D_2 , D_3 , D_{n-3} , D_{n-2} and D_{n-1} corresponding respectively to transformers T_1 , T_2 , T_3 , T_{n-3} , T_{n-2} and T_{n-1} . Delay lines D_1 through D_{n-1} are characterized in that they ideally possess the same delay as the respective corresponding transformer. Delay lines D_1 through D_{n-1} include inductive impedances 50, 51, 52, 53, 54 and 55, each of which have an impedance equal to the reference surge impedance Z . The impedances 50 through 55 are capacitatively coupled to conductive members 60 to 65, respectively, in a manner to provide the aforementioned delays for delay lines D_1 through D_{n-1} equal to that of the corresponding transformers T_1 through T_{n-1} , respectively. Conductive member 60 of delay line D_1 is referenced to ground. The low tension extremity of secondary winding 20 of transformer T_1 is connected through impedance element 50 of delay line D_1 and through conductive member 61 of delay line D_2 in the order named to the high tension extremity of pri-

mary winding 10 of transformer T_1 . Similarly, the high tension extremity of secondary winding 20 of transformer T_1 is connected through impedance element 51 of delay line D_2 and through conductive member 62 of delay line D_3 to the high tension extremity of primary winding 11 of transformer T_2 ; the high tension extremity of secondary winding 21 of transformer T_2 is connected through impedance element 52 of delay line D_3 and through conductive member 63 of delay line D_{n-3} to the low tension extremity of primary winding 13 of transformer T_{n-3} ; the low tension extremity of secondary winding 23 of transformer T_{n-3} is connected through impedance element 53 of delay line D_{n-3} and through conductive member 64 of delay line D_{n-2} to the high tension side of primary winding 14 of transformer T_{n-2} ; the high tension extremity of secondary winding 24 of transformer T_{n-2} is connected through impedance element 55 of delay line D_{n-1} to the high tension extremity of primary winding 15 of transformer T_{n-1} . In order to optimize the high frequency response, the delay of the delay lines D_1 through D_{n-1} should be the same as the delay of the corresponding transformer T_1 through T_{n-1} . Direct connections with no delay may be made if frequency response characteristics are not important.

In operation, a voltage E is applied across the input terminals 39, 40, the high side of the input voltage being applied to terminal 40. In that the delay through delay line D_1 is the same as the delay through transformer T_1 , a voltage E appears at the high side of primary winding 10 at the same time as the voltage flows through the winding 20 of transformer T_1 . The surge impedance

$$\frac{Z}{n-1}$$

between the windings 10, 20 causes the voltage to double at the high side of secondary winding 20. Subsequent current flow through the primary winding 10 maintains this voltage relationship. In the same manner, the voltage wave front propagates through delay line D_2 and transformer T_2 and through delay line D_3 and transformer T_3 until the last transformer, T_{n-1} , is reached. The high tension extremity of secondary winding 25 of transformer T_{n-1} produces an output voltage nE where the input T_{n-1} produces an output voltage nE where the input voltage applied to the input terminal 40 is E . The apparatus is characterized by the fact that the respective cores 30-35 are connected individually to an extremity of one of the primary or secondary windings of the transformers T_1 through T_{n-1} , respectively. Thus, the voltage difference between any of the cores 30-35 and any part of the windings 10 through 15 and 20 through 25 is never greater than E . This allows extremely high voltages to be generated without the normal winding-to-core breakdown limitation experienced in conventional transformers. In addition, the delay lines D_1 through D_{n-1} enable the transformer apparatus to operate under an extremely wide range of frequencies by causing the electrical impulses to propagate along both the primary and secondary windings at the same velocity.

Although the invention has been shown in connection with a certain specific embodiment, it will be readily apparent to those skilled in the art that various changes in form and arrangement of parts may be made to suit requirements without departing from the spirit and scope of the invention.

What is claimed is:

1. A high voltage transformer apparatus for generating an output voltage that is n times the amplitude of input voltage wherein n is no less than 3, said apparatus comprising first, second, third . . . $(n-3)$, $(n-2)$ and $(n-1)$ transformers of predetermined delay and each

possessing primary and secondary windings mutually coupled with individual cores, each of said primary and secondary windings having first and second terminals, the direction of polarity between respective first and second terminals being consistent and the respective turns ratio of said primary and secondary windings being substantially unity; means for connecting said first terminals of said primary and secondary windings of said first, second and third . . . $(n-2)$ transformers to said second terminals of said primary and secondary windings of said second, third . . . $(n-1)$ transformers, respectively; means for maintaining said second terminal of said primary winding of said first transformer at a reference potential level; and means connecting said respective second terminals of said secondary windings of said first, second, third . . . $(n-2)$, and $(n-1)$ transformers to said respective first terminals of said primary windings thereof whereby a voltage relative to said reference potential level applied to said second terminal of said secondary winding of said first transformer is transformed to n times its amplitude at said first terminal of said secondary winding of said $(n-1)$ transformer.

2. The high voltage transformer apparatus as defined in claim 1 wherein said means connecting said respective second terminals of said secondary windings of said first, second, third . . . $(n-2)$, and $(n-1)$ transformers to said respective first terminals of said primary windings thereof includes first, second, third . . . $(n-2)$ and $(n-1)$ delay elements, respectively, each of said delay elements introducing a delay substantially equal to said predetermined delay.

3. The high voltage transformer apparatus as defined in claim 2 wherein said first, second, third . . . $(n-2)$, and $(n-1)$ delay elements are referenced to said respective second terminals of said primary windings of said first, second, third . . . $(n-2)$ and $(n-1)$ transformers.

4. The high voltage transformer apparatus as defined in claim 1 wherein a reference impedance, Z , is defined as the square root of the product of the input and output impedances of said transformer apparatus and wherein the surge impedance of each of said first, second, third . . . $(n-2)$, and $(n-1)$ delay elements is equal to said reference impedance, Z , and the winding surge impedances of said first, second, third . . . $(n-2)$, $(n-1)$ transformers are equal to

$$\frac{Z}{n-1}, \frac{Z}{n-2}, \frac{Z}{n-3} \dots \frac{Z}{2}$$

and Z , respectively.

5. The high voltage transformer apparatus as defined in claim 1 wherein said individual cores of said first, second, third . . . $(n-2)$, $(n-1)$ transformers are referenced to said respective first terminals of said primary windings thereof.

6. A high voltage transformer apparatus having an output voltage that is n times the voltage applied thereto where n is an integer no less than three and wherein a reference impedance, Z , is defined as the square root of the product of the input and output impedances, said transformer apparatus comprising first, second, third . . . $(n-3)$, $(n-2)$, $(n-1)$ transformers of predetermined delay, each transformer possessing primary and secondary windings of substantially unity turns ratio coupled with individual cores and having first and second terminals, the direction of polarity between respective first and second terminals being uniformly in the same direction, said first, second, third . . . $(n-3)$, $(n-2)$, $(n-1)$ transformers having winding surge impedances equal to

$$\frac{Z}{(n-1)}, \frac{Z}{(n-2)}, \frac{Z}{(n-3)}, \dots \frac{Z}{3}, \frac{Z}{2}$$

and Z , respectively; means for connecting said first terminals of said primary and secondary windings of said first, second, third . . . $(n-3)$, $(n-2)$ transformers to said second terminals of said primary and secondary wind-

ings of said second, third . . . $(n-3)$, $(n-2)$, $(n-1)$ transformers, respectively; means for maintaining said second terminal of said primary winding of said first transformer at a reference potential level; first, second, third . . . $(n-3)$, $(n-2)$, $(n-1)$ delay lines each providing a delay equal to said predetermined delay and having a surge impedance equal to Z , said first, second, third . . . $(n-3)$, $(n-2)$, $(n-1)$ delay lines being referenced to said respective second terminals of said primary windings of said first, second, third . . . $(n-3)$, $(n-2)$, $(n-1)$ transformers, respectively; and means for connecting said respective second terminals of said secondary windings of said first, second, third . . . $(n-3)$, $(n-2)$, $(n-1)$ transformers through said first, second, third . . . $(n-3)$, $(n-2)$, $(n-1)$ delay lines, respectively, to said first terminals of said primary windings of said first, second, third . . . $(n-3)$, $(n-2)$, $(n-1)$ transformers whereby a voltage relative to said reference potential level applied to said second terminal of second secondary winding of said first transformer is transformed to n times its am-

plitude relative to said reference potential level at said first terminal of said secondary winding of said $(n-1)$ transformers.

5 7. The high voltage transformer apparatus as defined in claim 6 wherein said individual cores of said first, second, third . . . $(n-3)$, $(n-2)$, $(n-1)$ transformers are referenced to the respective first terminals of said primary windings thereof thereby to minimize the maximum voltage stress in said transformer apparatus.
